HYDRAULIC WELL JAR

Louis W. Chenault, 5015 Evergreen Lane, Victoria, Tex.
Filed Dec. 8, 1959, Ser. No. 858,178
14 Claims. (Cl. 166—178)

This invention comprises a novel and useful hydraulic well jar and more particularly relates to a device adapted to be connected to a drill string, a string of pipe or tubing or a wire line and to a fishing sub for automatically and by hydraulically controlled means effecting an upward jar or blow upon the fishing sub connected thereto.

In working deep wells such as those employed for recovering oil, gas or the like from great depths in the earth it is frequently necessary to recover a broken or stuck piece of pipe, rod, or the like, which has become accidentally or inadvertently stuck in the hole. A customary procedure for this purpose is to connect a fishing sub, suspended by a wire line, drilling or tubing string to the upper end of the stuck piece of pipe, or rod, commonly known as a fish and then effect mechanical blows or jars to the latter in order to loosen the same and facilitate its recovery.

It is therefore the object of the present invention to provide an improved hydraulically operated jar for this purpose.

A further object of the invention is to provide a hydraulically actuated jar in accordance with the foregoing object in which through the suitable control of the flow of hydraulic fluid therein, and in response to actuation of the jar by an upward pull upon the wire line, tubing or drill string to which the jar is attached, there is effected an initial slow upward movement of the hammer piston component of the jar until at a predetermined portion of its upward travel in the barrel of the jar a relatively free upward movement is permitted to thereby enable a violent blow, impact or jar to be applied to the barrel of the tool and thus to the fish secured to the lower end thereof.

A further important object of the invention is to provide a hydraulically actuated jar in accordance with the preceding objects, which will enable a relatively rapid reverse travel of the piston hammer within the jar in order to reset the device for use in effecting a subsequent jar or blow.

A further important object of the invention is to provide a hydraulically operated jar in accordance with the foregoing object wherein the jar itself shall be of simple construction, being provided with top and bottom closures, the former serving as an anvil upon which the piston hammer strikes and the latter serving as a control means to regulate the rate of movement and the action of the piston hammer within the jar.

A still further object of the invention is to provide a hydraulic jar in accordance with the preceding objects wherein a very simple control means for the hydraulic action is provided, the same including a bore or control chamber formed in the lower end of the piston hammer, by-pass passages extending through the piston hammer and intersecting this bore, and with the control means consisting of a control piston carried by the bottom closure member and being slidably received within the bore and controlling communication of the by-pass passages therewith.

And a final important object of the invention to be specifically enumerated herein resides in the provision of a hydraulic jar which shall be of simple, compact and inexpensive construction, yet one which shall be highly effective and efficient for the purposes intended.

These together with other objects and advantages which will become subsequently apparent reside in the details

2

of construction and operation as more fully hereinafter described and claimed, reference being had to the accompanying drawings forming a part hereof, wherein like numerals refer to like parts throughout, and in which:

5 FIGURE 1 is a view showing in section a portion of a well bore and illustrating the manner in which the hydraulic jar in accordance with this invention is disposed therein for operation by a drill string or the like, the upper end of the jar being broken away and shown in vertical section to indicate the position of the parts therein after the piston hammer of the jar has delivered its impact to the anvil at the upper end of the jar;

10 FIGURE 2 is a view similar to FIGURE 1 but having a lower portion of the barrel of the jar broken away and showing the position of the piston, of the jar at the lower end of the position and travel in the barrel of the jar in readiness for beginning its upward hammer stroke;

15 FIGURE 3 is an enlarged view in vertical section 20 through the jar showing the internal construction of the piston hammer, the anvil and the control means for the jar and indicating the manner of attaching the jar to the lower end of a drill pipe, tubing string or wire line, and showing the manner in which the lower end of the jar is attached to a fishing sub;

25 FIGURE 4 is a horizontal sectional view taken substantially upon the plane indicated by the section line 4—4 of FIGURE 3;

30 FIGURE 5 is a perspective view of the closure plug 30 for the bottom end of the jaw;

35 FIGURE 6 is a view similar to FIGURE 3 of the upper portion of the jar but showing a slightly modified construction in which the well fluid may be employed as the liquid medium for controlling the operation of the jar; and

40 FIGURE 7 is a horizontal sectional view taken substantially upon a plane indicated by section line 7—7 of FIGURE 6.

45 In FIGURES 1 and 2 of the accompanying drawings, the numeral 10 designates a portion of a well bore in which is shown suspended at 12 a portion of a suitable supporting actuating means for the jar which itself is indicated by the numeral 14. Coupled to the lower end of the jar is a fishing sub 16 of any suitable construction and by means of which the jar may be secured at the upper end of a piece of a stub pipe, tubing or other fish in order to loosen the same and permit the fish to be removed from the well bore after loosening.

50 The member shown 12 may consist of any of the usual means for supporting and operating the jar such as a drill string, a string of tubing or pipe or the like, or even a wire line with an appropriate swivel for connecting the same to the jar.

55 Referring now especially to FIGURE 3 it will be seen that the jar 14 consists of a hollow body comprising a cylindrical barrel 20 which is open and internally threaded at its top and bottom ends, being provided with top and bottom closure plugs as at 22 and 24 respectively. In the embodiment of FIGURES 1-5, the top closure plug 22 is provided with a central bore 26 therethrough provided with a suitable O-ring or other packing means 28 to establish a sealed engagement with the operating stem 30 of a piston and hammer 32 slidably received in the chamber in the interior of the body 20.

60 As will be observed from FIGURE 3, the piston hammer 32 divides the interior of the chamber into top and bottom compartments 34 and 36 respectively, which compartments are filled with a suitable hydraulic fluid of any desired character which is designed or intended to dampen and control the rate of travel of the piston hammer within the chamber as set forth hereinafter.

65 The operating rod 38 which extends slidably through

the bore 26 of the top closure plug 22 is in turn provided with a connector 38 having an externally threaded upper end 40 received in the internally threaded bore 42 of the lowermost section of the string 12. The operating rod 30 is preferably provided with a laterally enlarged or flanged portion as at 44 which is adapted to abut the upper end of the top closure plug 22 to limit downward travel of the piston hammer 32 and if desired to prevent the bottom surface of the latter from striking the bottom closure plug 24.

It should here be understood that the top closure plug 22 comprises an anvil having a flat annular bottom surface 46 against which the top surface of the piston hammer 32 is adapted to strike or engage when the piston hammer is moved to the uppermost position in the top compartment 34 of the barrel of the jar in the position shown in FIGURE 1.

A hydraulic control means is provided for regulating the rate of travel of the piston hammer within the chamber of the hollow body in a manner and for a purpose to be now described.

An axial bore 50 extends upwardly from the bottom face 52 of the piston hammer 32 and into the operating rod 30 to provide a control chamber 54 therein. A plurality of by-pass passages 56 constitute by-pass means which at one end intersect the previously mentioned bore 50 of the control means adjacent the lower end of the latter, and at their upper ends open upon the annular shouldered surface 58 upon the top side of the piston hammer 32 and thus establish communication with the upper compartment 34. The by-pass means, except when controlled as set forth hereinafter does establish uninterrupted communication between the top and bottom chambers 34 and 36. When the by-pass means are open, it is obvious that the piston is free to travel in the chamber and the hollow interior of the body 20 between its lowermost and its uppermost position without substantial hindrance by the fluid contained in these chambers, and thus can deliver an impact or blow upon the anvil comprising the top closure plug 22.

In order to facilitate downward or reverse movement of the piston within the chamber of the body there is provided a return means consisting of one or more fluid return passages 60 whose upper ends intersect the by-pass passages 56 intermediate the ends of the latter, and whose lower ends open as at 62 through the bottom surface 52 of the piston hammer into the bottom compartment 36. A non-return check valve 64 together with a spring 66 comprises conventional means which will permit ready flow of fluid from the bottom compartment 36 to the upper compartment 34 upon downward movement of the piston hammer but will prevent reverse flow therethrough.

It is preferred, as shown in FIGURE 3 to provide an O-ring or seal as at 70 upon the circumference of the piston hammer to establish a fluid-tight sealing engagement of the latter with the wall of the chamber in which the piston hammer is slidably disposed.

The control means further includes a control piston or control valve 72 which is slidably received in the bore 50 and chamber 54 and which is mounted upon and carried by the upper end of the bottom closure plug 24. It will thus be seen that the member 74 is stationarily mounted and that relative sliding movement between the valve of piston member 72 and the by-pass passages is effected by vertical reciprocation of the piston hammer 32 and its piston rod or operating rod 30.

The arrangement is such that there is sufficient clearance provided between the piston 72 and the wall of the bore 50 to enable a slow leakage of fluid through the by-pass passage 52 and into or out of the chamber 54 as the piston is slowly pulled upward in the barrel of the device by upward thrust imparted to the operating rod 30 by the string 12. It will be understood that the weight of the barrel 20 and of the sub 16 attached thereto and of the

fish when the sub is attached to the latter will resist this upward pull and thus cause a relative upward travel of the piston hammer within the chamber of its barrel.

It will be understood that this upward travel during the initial portion thereof is necessary relatively slow, being limited to the rate at which hydraulic fluid can leak from the chamber 34 through the by-pass means and pass through control piston 72 into the chamber 36. However, when this upward travel has reached such an extent that the upper end of the control piston 72 clears the lower end of the by-pass passages 56, there has been established a substantially unimpeded flow of fluid between the two chambers so that the piston hammer 32 can now travel rapidly upwardly until its top surface 58 strikes the anvil surface 46 of the top closure plug 22 and thus delivers the desired upward impact or blow to the body 20, to the closure plug 24 carried thereby and from the latter to the fishing sub 16.

When the lifting member 30 is again lowered, the weight of the same will cause the piston hammer to travel rapidly downwardly within the chamber within the body 20 and the return means consisting of the valve 64 and the associated passage arrangement will permit such return movement to occur rapidly.

Obviously, a series of such impulses can thus be given to effect loosening of the fish and facilitate its recovery by the device.

In the device as so far described, it will be understood that the hydraulic fluid employed to control the rate of movement of the piston hammer within the jar is completely sealed within the device in a self-contained system. It is however possible to employ the same principle of operation in a device in which the well fluid itself is employed as the hydraulic fluid controlling the operation of the device. In this arrangement the structure is identical to that previously described except for a modification shown in FIGURES 6 and 7. In this arrangement, the O-ring 28 is omitted from the top closure plug 22 and a somewhat larger clearance as at 80 is provided between the top closure plug 22 and the adjacent surface of the operating or piston rod 30. Consequently, drilling mud or other well fluid can readily flow into the top chamber 34 of the barrel 20 above the piston hammer therein and this fluid will operate to regulate the rate of upward travel by means of the by-pass passage means and the return means in the same manner as described in connection with the preceding embodiment.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be restored to, falling within the scope of the invention as claimed.

What is claimed as new is as follows:

1. A hydraulic jar comprising a hollow body having a chamber therein with top and bottom closures, a piston hammer slidably in said chamber and having an operating stem slidably extending through said top closure, said piston hammer having a fluid tight seal engaging the wall of said chamber at all times and dividing said chamber into top and bottom compartments, said body having a surface disposed in the range of movement and path of travel of said piston hammer and constituting an anvil for the latter, a by-pass means establishing communication between said compartments on opposite sides of said piston hammer for flow of hydraulic fluid therebetween, a control means in said body for establishing slow leakage of fluid from the top to the bottom compartment during the initial upward movement of said piston hammer in said chamber and establishing unrestricted flow during the remainder upward movement of said hammer piston, said control means being disposed in said by-pass means

for controlling flow through the latter between said top and bottom compartments.

2. The combination of claim 1 wherein said chamber is of a uniform diameter throughout at least that portion thereof which is traveled by said piston hammer.

3. The combination of claim 1 wherein said by-pass means comprises passages extending through said piston hammer, said passages being inclined inwardly from their upper ends adjacent the periphery of the piston hammer to their lower ends adjacent the longitudinal axis of said piston hammer, said control means comprising a member movable in one of said passages and controlling flow therethrough.

4. A hydraulic jar comprising a hollow body having a chamber therein with top and bottom closures, a piston hammer slidable in said chamber and having an operating stem slidably extending through said top closure, said piston hammer dividing said chamber into top and bottom compartments, a by-pass means establishing communication between said compartments on opposite sides of said piston hammer for flow of hydraulic fluid therebetween, a control means in said body for establishing slow leakage of fluid from the top to the bottom compartment during the initial upward movement of said piston hammer in said chamber and establishing unrestricted flow during the remainder upward movement of said piston hammer, said piston hammer having a bore extending upwardly from the bottom surface thereof and comprises a control chamber, said by-pass means comprising passages in said piston hammer having one end of each opening into said upper compartment and having the other end of each opening into said bore, said control means including a member slidably received in said bore and restricting and throttling flow of fluid between said control chamber and said passages.

5. The combination of claim 4 wherein said control means member consists of a piston valve relatively slidable in said bore and throttling the communication of the latter with said passages.

6. The combination of claim 5 wherein said piston valve is carried by said bottom closure.

7. A hydraulic jar comprising a hollow body having a vertically elongated chamber therein with top and bottom closures, a piston hammer slidable with fluid-tight engagement within said chamber and dividing the latter into top and bottom compartments, said piston hammer including an operating stem through which relative movement is given to said piston hammer in said chamber, said body having an anvil engageable by said piston hammer during its sliding movement in one direction, by-pass means in said piston hammer for flow of fluid between said compartments, control means disposed in said by-pass means for restricting rate of flow through said by-pass means during the initial portion of upward travel of said piston hammer

in said chamber and for effecting unrestricted rate of flow through said by-pass means during the initial portion of upward travel of said piston hammer in said chamber and for effecting unrestricted rate of flow through said by-pass means during the remainder of the upward travel of said piston hammer in said chamber, said control means comprising a bore in said piston hammer extending vertically upward from the bottom face of said piston hammer and a piston valve stationarily mounted in said chamber and 10 having sliding fit in said bore with a slow rate of leakage therebetween, said by-pass means including a passage in said piston hammer establishing continuous communication between said top compartment and with said bore by an inlet port at an intermediate location in the latter, said 15 piston hammer and piston valve being so positioned that said piston valve will cover said inlet port during said initial portion of said upward travel and will uncover said inlet port during said remainder of said upward travel, fluid return means establishing flow between said compartments and including a non-return valve preventing flow from the top to said bottom compartment but allowing free reverse flow.

8. The combination of claim 7 wherein said return means extends through said piston hammer.

25 9. The combination of claim 8 wherein said return means communicates with said by-pass means.

10. The combination of claim 1 including fluid return means including a check valve for establishing one way communication between said compartments for effecting 30 flow of fluid from the bottom to the top compartment.

11. The combination of claim 10 wherein said return means extends through said piston hammer.

12. The combination of claim 11 wherein said return means communicates with said by-pass means.

35 13. The combination of claim 1 wherein said top closure comprises said anvil engageable by said piston hammer.

14. The combination of claim 1 wherein said top closure comprises said anvil engageable by said piston hammer, and said control means includes a piston valve carried 40 by said bottom closure.
